UNITED STATES PATENT OFFICE

172,779

SLIDE PROJECTOR

Theodore S. Briskin, Chicago, Ill., and John E. Davis, Sherman Oaks, Calif., assignors to Revere Camera Company, Chicago, Ill., a corporation of Delaware

Application February 10, 1954, Serial No. 28,936

Term of patent 14 years

(Cl. D61—1)

To all whom it may concern:

Be it known that we, Theodore S. Briskin, and John E. Davis, citizens of the United States, residing at Chicago, State of Illinois, and Sherman Oaks, State of California, respectively, have invented a new, original, and ornamental Design for a Slide Projector, of which the following is a specification, reference being had to the accompanying drawings, forming a part hereof.

Fig. 1 is a plan view of a slide projector showing our new design;

Fig. 2 is a side elevation view thereof;

Fig. 3 is a front elevation view thereof, and

Fig. 4 is an elevation view thereof of the side opposite that shown in Fig. 2.

We claim:

The ornamental design for a slide projector, as shown.
